MACHINE FOR SPLITTING OR BREAKING PAVING BLOCKS

Filed Sept. 17. 1921

2 Sheets-Sheet 2

UNITED STATES PATENT OFFICE.

JOSEPH PETERMANN, OF PHILADELPHIA, PENNSYLVANIA.

MACHINE FOR SPLITTING OR BREAKING PAVING BLOCKS.

Application filed September 17, 1921. Serial No. 501,236.

To all whom it may concern:

Be it known that I, JOSEPH PETERMANN, a citizen of the United States, residing at Philadelphia, in the county of Philadelphia, 5 and State of Pennsylvania, have invented new and useful Improvements in Machines for Splitting or Breaking Paving Blocks, of which the following is a specification.

This invention relates to machines for splitting or breaking stone blocks and the like and it has more particular reference to machines which are adapted by means of a power-driven hammer for breaking or splitting paving-blocks of concrete or other homogeneous nature and substance squarely into two parts so that the operation of street or roadbed paving may be effectively carried out with the proper broken joints so vitally essential to proper paving.

20 The primary object of my invention is to provide a novel means whereby the shocks incidental to stone or paving block severance by power-driven hammer devices are effectively absorbed.

25 Another object of this invention is the provision of a novel paving block splitting or breaking machine which is automatic in action.

Further objects of this invention consist 30 in the provision of a novel paving block splitting or breaking machine which is simple to construct, automatic in action, effective in use, not liable to get out of order, and which ensures the purposes for which it 35 has been devised far more efficiently than any other analogous structure heretofore produced.

With the foregoing and other objects in view my invention consists essentially in the 40 novel features of construction, combinations and arrangements of parts hereinafter fully described, and more specifically defined by the appended claims.

In the further disclosure of the invention 45 reference is to be had to the accompanying sheets of drawings constituting a part of this specification, and in which like characters of reference denote the same or corresponding parts in all the views.

50 Figure 1—is a front end elevation of a paving block splitting or breaking machine having my improvements applied thereto.

Figure 2—is a part sectional and fragmentary side elevation of the same.

55 Figure 3—is a perspective view of the

anvil block and trip mechanism hereinafter fully described.

Referring to the drawings and in accordance with my invention I construct an underframe or body 4 adapted for transportation on road wheels 5, said underframe or body being of strong and durable character and having built thereon spaced vertical standards 6 conveniently of channel cross-section braced by rods 7 and serving as supports for a power-hammer 8 of appropriate type that shown representing an Ingersoll-Rand pneumatic hammer. In order to provide a more convenient means whereby the power-hammer 8 may be raised and lowered 60 relative to the standards 6 for regulating or varying the stroke I substitute a gear wheel 9 for the usual crank provided for this purpose, said gear wheel 9 meshing with a larger toothed wheel 10 on the upper end 65 of a vertical rod or shaft 11 journaled at 12, 12 in appropriate bearings and rotatable by means of a hand-wheel 13 at its lower end. Thus it will be seen that a simple and effective means is provided for varying the hammer's stroke, said means being within easy 70 reach of the operator and obviating the necessity of climbing on the machine which has hitherto been required to operate the crank handle above referred to.

The usual adjustable guide-rods are designated by the numeral 14, their lower ends being screw threaded into the brackets 15 secured to the underframe or body 4 in the well known way, whilst the customary bridge 75 spring is indicated by the numeral 16, its purpose and function being well understood.

In order to effectively absorb the shocks incident to the operation of the hammer 8, I make a substantially V-shaped yoke 17, 80 the limbs whereof are broadened out at 18 and laterally flanged at 19 and provided with holes 20 for the passage therethrough of the adjustable guide rods 14, and said V-shaped yoke is securely bolted or otherwise 85 attached at 21 to the tool holder 22. Strong compression springs 23 are interposed between the flanges 19 and lock nuts and washers 24 on the guide rods 14, it being of course well understood that the lock nuts 100 make provision for the adjustment of the springs 23 as required.

The anvil block 25 preferably consists of a rectangularly cut piece of hard lumber reinforced at its lower front and back edges 105

by opposed channel irons 26 conveniently anchored thereto by through bolts 27, and said anvil block is supported on a shoe or hard lumber sled 28 suitably attached to the 5 underframe 4 by eye bolts 29, links 30 and stay rods 31. Thus it will be seen that the anvil block 25 can be readily trailed along as the machine is moved about without disconnection therefrom, and in order to ensure the 10 proper anchoring of said anvil block I preferably employ rods 32 fitted with turnbuckles 33, whereby they can be accurately adjusted. At the same time it is to be noted that whenever desired the anvil block 25 15 and sled 28 can be easily disconnected and otherwise transported when the machine is traveled long distances or over rough and uneven road surfaces.

Seated within a pocket or recess 34 in 20 the upper part of the anvil block 25 is a splitting or wedge member 35 with which and in direct alignment thereover is the splitting tool 36 carried by the aforesaid tool holder 22; and in order to provide a 25 simple means whereby the wedge member 35 may be promptly removed for re-grinding or renewal I provide a horizontal boring 37 in the anvil block 25 for the insertion of an appropriately pointed or shaped 30 implement which can be driven beneath said member 35 to lift or release same when it has become jammed in the pocket or recess 34 as will be perfectly obvious to those acquainted with the art and use of machines of the nature described hereinbefore.

An appropriate trip rod 38 connects from the control cock or valve 39 in the air line 40 to a pedal lever 41 for starting and stopping the hammer 8.

40 In order to protect the hands and arms of the operator I provide a guard device conveniently comprising elbowed members 42 mounted on and outwardly projecting from a rock shaft 43 journaled in bearings 45 44 transversely relative to the brackets 15 hereinbefore described, a stop member or angle iron 45 serving to support the rock levers away from contact with the anvil. It is to be noted that the lateral parts 46 50 of the elbowed members 42 serve as arm or wrist supports for the operator when placing a block on the wedge member 35 for splitting, and that said elbow members 42 automatically lift when passing a paving block or the like thereunder.

Still further I desire it to be most particularly noted that by the use and employment of the V-shaped yoke 17, and its rigid securing to the tool holder 22 the latter is 60 prevented from turning whereby the tool 36 remains always in correct alignment with the wedge member 35 a very important factor in ensuring a clean split or breaking of the paving block. Still another point to be observed is the notchings

47 provided in the upper edge of the wedge member 35 which accommodate undulations or the like in used blocks that it is desired to split or break.

From the foregoing description the use 70 and operation of my improved paving block splitting or breaking machine will be clearly apparent without further description, and whilst I have shown and particularly described a preferred embodiment of the invention 75 it will be obvious the same is susceptible of detail changes and variations without departing from its essential features, and the right is hereby reserved to make such changes and modifications therein as fairly lie within the scope of the appended claims.

Having described my invention, what I claim as new and desire to secure by Letters Patent is:

1. In a machine for splitting or breaking paving blocks the combination with a vehicular underframe and a power actuated tool adjustably mounted thereon, of an anvil adjustably connected thereto, a notched wedge shaped member projecting above and seated in a pocket in the upper face of said anvil in direct alignment with the power actuated tool, a sled for supporting said anvil removably anchored to the vehicle underframe, a V-shaped yoke having lateral flanges through which pass the power actuated tool guide rods, compression springs between said lateral flanges and lock nuts threaded on the guide rods, said yoke being secured to the tool holder whereby the latter is prevented from turning, and means for varying the stroke of the tool.

2. In a machine for splitting or breaking paving blocks the combination with a vehicular underframe and a power actuated tool adjustably mounted thereon, of an anvil adjustably connected thereto, a notched wedge shaped member projecting above and seated in a pocket in the upper face of said anvil in direct alignment with the power actuated tool, a sled for supporting said anvil removably anchored to the vehicle underframe, a V-shaped yoke having lateral flanges through which pass the power actuated tool guide rods; compression springs between said lateral flanges and lock nuts threaded on the guide rods, said yoke being secured to the tool holder whereby the latter is prevented from turning, means for varying the stroke of the tool, means for manually controlling the operation of the tool, and guard mechanism for protecting the hands of the operator.

3. In a machine for splitting or breaking paving blocks the combination with a vehicular underframe and a power actuated tool adjustably mounted thereon, of an anvil adjustably connected thereto, a notched wedge shaped member projecting above

and seated in a pocket in the upper face of said anvil in direct alignment with the power actuated tool, a sled for supporting said anvil removably anchored to the vehicle underframe, a V-shaped yoke having lateral flanges through which pass the power actuated tool guide rods; compression springs between said lateral flanges and lock nuts threaded on the guide rods, said yoke being secured to the tool holder whereby the latter is prevented from turning, means

for varying the stroke of the tool, means for manually controlling the operation of the tool, and guard mechanism for protecting the hands of the operator, said means comprising spaced elbow members carried by a rock shaft supported at the back of the anvil, and a stop bar for preventing the elbow members from falling on the upper face thereof.

In testimony whereof I affix my signature.

JOSEPH PETERMANN.
